UNITED STATES PATENT OFFICE.

HENRY STEPHENS, OF CLEVELAND, OHIO, ASSIGNOR TO THE INTERSTATE RAILWAY SUPPLY COMPANY, OF CLEVELAND, OHIO, A CORPORATION OF OHIO.

RAIL ANCHOR.

Application filed October 23, 1922. Serial No. 596,369.

To all whom it may concern:

Be it known that I, HENRY STEPHENS, a citizen of the United States, and a resident of Cleveland, county of Cuyahoga, and State of Ohio, have invented a new and useful Improvement in Rail Anchors, of which the following is a specification, the principle of the invention being herein explained and the best mode in which I have contemplated 10 applying that principle, so as to distinguish it from other inventions.

The present invention relates to devices for resisting the creeping action of railroad rails and ties and more particularly the present 15 invention relates to an improved device for this purpose which will more effectively grip the rail. The present device or rail anchor is of improved construction whereby the necessary strength is obtained and at the 20 same time the device is economical of manufacture and easy to install or remove. To the accomplishment of the foregoing and related ends, said invention, then, consists of the means hereinafter fully described and 25 particularly pointed out in the claims.

The annexed drawing and the following description set forth in detail certain mechanism embodying the invention, such disclosed means constituting, however, but one 30 of various mechanical forms in which the principle of the invention may be used.

In said annexed drawing:

Fig. 1 is a perspective view of my improved rail anchor; Fig. 2 is a perspective view of the wedge member; Fig. 3 is a plan view of a rail section showing the application of the device; Fig. 4 is a section on the line 4—4 of Fig. 3; Fig. 5 is a broken top plan view on enlarged scale, and Fig. 6 is a plan view of a rail section showing a modified form of anchor embodying two-way holding means.

The present anchor is adapted to be located beneath the railroad rail and is adapted to grip the base flange of the rail and at the same time contact one of the ties.

As illustrated, the anchor comprises an upright bar or strap 1 having a U-shaped bend 2 therein, the bar being cut away to 50 form an overhanging projection 3 at the end near the U-bend and sloping downwardly toward the other end to form a rail

base contacting surface 4 with a second overhanging projection 5 at the end away from the U-bend.

The overhanging end 3 forms a hook under which one end of the rail base 6 is adapted to fit snugly while the other hooked end or overhanging portion 5 receives the rail flange and this flange is secured tightly thereto by means of a wedge 7 which may be forced between the end and top of the recess below the hook and the rail flange. This overhanging portion 5 presents a notch or recess of sufficient width and depth so as to provide a space between the vertical edge 8 of the overhanging portion and the end of the rail flange and also a space between the horizontal surfaces 9 and 10 respectively of the overhanging portion and the rail flange. The wedge is shaped to fit in this curved space and thus the rail is wedged tightly as the wedging action is both horizontal and vertical.

The wedge 7 is formed at the side engaging the anchor with a series of notches forming shoulders 12 which engage past the edge of the anchor to hold the wedge in position.

The present anchor is placed upon the rail with the back 13 of the U-bend against the tie and then the wedge is driven into place which tends to and does cause the anchor to turn slightly or to assume a position at an angle to the rail. Furthermore the U-bend imparts sufficient elasticity to the bar to permit of its stretching so as to cause the anchor to bind against the tie and at the same time grip the rail tightly.

In Fig. 6 a two-way anchor is shown, the main portion of the anchor being identical in construction with the form previously described. In this form at the wedging end the anchor is provided with an extended portion 20 which is bent at right angles to the body of the anchor and has a flange 21 parallel to the body forming together an L-flange having one or more apertures 22 through which a tie engaging member 23 such as a screw or spike may be driven into the tie. This secures the anchor to the tie against movement away therefrom and to allow the anchor to function properly in the normal direction the face 24 of the flange

is spaced slightly away from the tie, but the head of the spike or screw should be flush against the outer face of the flange.

Any suitable tie engaging means may be used in place of the L-flange shown but such means must not spring the anchor during application as such springing tends to loosen the wedges. This end securing means must be such as to allow the anchor to function naturally in holding in the usual direction and at the same time hold against rail movement in the opposite direction.

When the anchor is in place and the rail starts to creep, the U-bend is forced tight against the tie causing a further binding of the anchor to the rail or a tightening of the grip thereon to prevent further creeping. While the anchor should be normally positioned against the tie in originally positioning the same a slight clearance will quickly be taken up as the rail creeps and further creeping is quickly prevented.

The present anchor is simple in construction but is strong and yet has the necessary resiliency and elasticity to grip the rail tightly due to the U-bend spring in the main body of the anchor. By sloping the rail base surface of the anchor added material is given to the hooked end where the wedging action is maintained, thereby greatly strengthening the anchor at this point and at the same time the material in the anchor is gradually reduced toward the end 5. The device is easy to attach and holds securely but may be released if necessary and the material is so arranged as to give strength and stiffness where required and at the same time the necessary spring action.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. A rail anchor comprising a flat upright member formed with a U-bend intermediate the ends and adjacent one end, the top of said member being cut away to form two hooked ends adapted to engage over the base flange of the rail, and a wedge adapted to be forced between the base flange and one hooked end to secure said anchor to said base flange.

2. A rail anchor comprising a flat upright member formed with a U-bend intermediate the ends and adjacent one end, said bend being adapted to act as an abutment against the rail tie, the top of said member being cut away to form two hooked ends adapted to engage over the base flange of the rail, and a wedge adapted to be forced between

the base flange and one hooked end to secure said anchor to said base flange.

3. A rail anchor comprising a member having hooked ends and a single U-bend spring adjacent one of said ends, said hooked ends being adapted to be engaged with the base flange of a rail and said U-bend spring being adapted to be in contact with a rail tie and a wedge adapted to engage between one of said hooked ends and the base flange and adapted upon being forced tightly therebetween to cause said anchor to tightly grip said base flange and said U-bend spring being adapted to abut against the tie to act as a fulcrum to cause said anchor to grip the rail base more tightly upon creeping action of the rail.

4. A rail anchor comprising a flat upright member having overhanging ends and a sloped rail flange engaging surface making the upright member wider at one end than at the other, said member being provided between its ends with a tie-contacting U-bend spring positioned adjacent the wider end, and a separate wedge member adapted to be forced between the hooked end away from said U-bend spring and the base flange to secure said anchor tightly to said flange.

5. A rail anchor comprising a flat upright member having overhanging ends and a sloped rail flange engaging surface making the upright member wider at one end than at the other, said member being provided between its ends with a tie-contacting U-bend spring positioned adjacent the wider end, and a separate wedge member adapted to be forced between the hooked end away from said U-bend spring and the base flange to secure said anchor tightly to said flange and against the tie, said U-bend and narrowing member imparting elasticity to said bar and being adapted to cause said anchor to grip the rail base flange more tightly upon creeping action of the rail.

6. A rail anchor comprising a flat upright member having overhanging ends and a sloped rail flange engaging surface making the upright member wider at one end than at the other, said member being provided between its ends with a U-bend spring positioned adjacent one end, and a wedge member adapted to be forced between the overhanging end opposite to said U-bend spring and said rail base flange to secure said anchor to said rail, said U-bend spring being adapted upon creeping movement of the rail to spring and more tightly grip the anchor to the rail.

7. A rail anchor comprising a flat upright member having overhanging ends and a sloped rail flange engaging surface making the upright member wider at one end than at the other, said member being provided with a tie-contacting U-bend spring adjacent the wider end, and a separate wedge

- member adapted to be forced between the hooked end away from said U-bend spring and the base flange to secure said anchor tightly to said flange, said wedge member 5 having a series of notches on its anchor engaging face to catch back of the hooked end to prevent accidental removal of the wedge.
8. A rail anchor comprising a member having a U-bend spring adjacent one end 10 and a rail base flange engaging portion, and a flange at the opposite end adapted to be secured to a tie, means for securing said anchor to the rail base flange and means for fastening said end flange to the tie to allow said anchor to hold in both directions.
9. A rail anchor comprising a member adapted to be positioned beneath a rail, said member having end portions adapted to grip the base flange of the rail and a U-bend 15 spring adapted to act as a fulcrum against the rail tie, said member being provided at one end with an L-flange adapted to be secured to the tie to allow the anchor to hold in both directions.
10. A rail anchor comprising a member 20 adapted to be positioned beneath a rail, said member having end portions adapted to grip the base flange of the rail and a U-bend spring adapted to act as a fulcrum against the rail tie, said member being provided at one 25 end with an L-flange having an aperture adapted to receive a tie engaging member to hold said anchor to said tie to allow said anchor to hold in both directions.

Signed by me this 20th day of October, 35
1922.

HENRY STEPHENS.
